UNITED STATES PATENT OFFICE.

WILLIAM KAUTZ, OF WILLARD, OHIO.

FIRE ESCAPE.

Application filed November 29, 1926. Serial No. 151,480.

This invention relates to new and useful improvements in fire escapes of the collapsible chain type, and has for its primary object to provide such a device that may be 5 readily wrapped or wound within a cabinet preferably of the type shown and described in my copending application Serial No. 151,479 filed on even date herewith so that the same will be out of the way when not 10 in use.

A further and important object is to provide a fire escape of this character that may be readily dropped from one of the upper stories of the building and rigidly secured 15 to the sill of a window so that persons may descend from the building without great liability of the ladder becoming disconnected from said sill.

A still further object is to provide a ladder 20 of this character that is relatively simple of construction, inexpensive of manufacture, and one that is highly well adapted for all 25 the purposes intended.

With the foregoing and other objects 25 which will become apparent as the nature of the invention is better understood, the same comprising the novel form, combination, and arrangement of parts hereinafter more fully described, shown in the accompanying drawings and claimed.

In the drawings wherein like reference characters indicate corresponding parts throughout the several views:

Figure 1 is a fragmentary front side elevation of a building upon which is disposed a fire escape constructed in accordance with the present invention.

Figure 2 is a detail vertical section thereof for disclosing the fire escape in side elevation.

Figure 3 is a top plan view of the window sill engaging unit for the purpose of securing the escape to the building.

Figure 4 is an enlarged perspective of one 45 of the side arms of said unit.

Figure 5 is a perspective of one of the plate links that facilitate the interconnection of certain chain sections as well as the pivotal connection of the ladder steps thereto.

Figure 6 is a perspective of one of said ladder steps, and

Figure 7 is a perspective of a cross bar at the lower end of the fire escape to facilitate the anchoring of said end to the building.

Now having particular reference to the drawings wherein there is disclosed the most

practical embodiment of the invention with which I am at this time familiar, the device consists of a pair of inner, and a pair of outer chains designated respectively 5-5 and 6-6. 60 The outer chains 6-6 are of a single length, while the inner chains 5-5 are composed of chain lengths interconnected by plate links 7 that have openings in the opposite ends as clearly indicated in Figure 5 so that the 65 ends of the chain sections may be secured thereto. These link plates 7 are each further formed centrally with an opening 8, the 70 openings of transversely aligned plates receiving the laterally bent and threaded ends 9-9 of U-bar steps or rungs 10. Said ends being secured in the opening by nuts as 75 clearly indicated in Figures 1 and 2. The central bar member of each step or rung 10 is provided at its inner side and in spaced 80 relation to its opposite ends with loops 11 with which engage the outer chain lengths, whereby inward sliding movement of said chain lengths is prevented. The lower ends of the chains 5-5 and 6-6 are connected to 85 the opposite ends of a cross bar 12 that is formed centrally and at its upper edge with a V-notch 13, for a purpose hereinafter more fully described.

Permanently secured to the upper ends of the inner chains 5-5 is a window sill attaching unit designated generally by the reference character 14. This unit consists of a pair of side arms 15-15 of flat metal formation, the inner ends of which are hooked 90 as at 16 for engagement beneath the inner sill board of the window B at the uppermost floor of the building A. These hooked ends 16 of the arms 15-15 of said unit 14 are interconnected by a cross bar 17, while the 95 arms are further interconnected at their centers and at their outer ends by other bars 18 and 19. The outer ends of said arms 15-15 are formed with depending plates 20, see Figure 2, the lower edges of which 100 will rest upon the outer edge of the sill of said window B as clearly indicated in Figure 2. From these plates are outwardly projecting depending tongues 21, while disposed upon the inner sides of the tongues and plates are similarly shaped reinforcing plates 22, the tongue portions thereof as well 105 as the tongues of the arms being provided with registering openings so as to facilitate the attachment of the upper ends of the 110 innermost chain 5-5 thereto.

Connected to the center bar 18 of the unit

14 is a pair of chain lengths 23-23 that are provided at their free ends with spring locking hooks 24-24 so that the upper ends of the outer chains 6-6 may be connected thereto for preventing the swinging of the steps or rungs 10 when the fire escape is in use.

Secured to the outer side of the building at the foundation thereof and directly beneath the center of the window to which the upper end of the fire escape is to be attached is an outwardly extending flat-like bar 25 to the outer end of which is pivoted a lever 26. Obviously after the fire escape 10 has been dropped from the window it will be necessary for a person standing upon the ground to pass the connecting bar 12 for the lower ends of the inner and outer chains 5-5 and 6-6 beneath the lever 26 after 15 which a downward swinging of the same will force said bar inwardly beneath the bar 25 for securing the fire escape against swinging movement. When it is desired to remove the device from the building it is only necessary that the lower end thereof be disconnected from the bar 25 after which the unit 14 at the upper end of the device may be 20 arranged upon the support or the stand shown and described in my copending application. The outer chains 6-6 are then detached from the chain sections 23-23 after 25 which the steps or rungs 10 will swing downwardly upon the link plates 7 so as to permit of the winding of the device within the stand.

The bar 25 is a fixed bar, and the lever 26 is designed to normally depend from the outer end of the bar 25. The upward pull on the bar 12 is against the under side of the bar 25, and consequently when the lever 26 is made sufficiently heavy, said lever 26 40 may be depended upon to prevent casual disengagement or release of the bar 12 from the bar 25.

It will thus be seen that I have provided a highly novel, simple, and efficient fire escape that is well adapted for all the purposes heretofore designated, even though I have herein shown and described the invention 45 as consisting of certain detail structural elements, it is nevertheless to be understood that minor changes may be made therein without affecting the spirit and scope of the appended claims.

Having thus described the invention, what I claim as new and desire to secure by Letters Patent is:—

1. In a fire escape of the class described, a plurality of chain lengths adapted for vertical disposition on the outside of a building, ladder steps arranged at predetermined spaced intervals throughout the chain lengths, a window sill attaching unit at the

upper ends of the chain lengths, a cross bar secured at its ends to the lower ends of the chain lengths, and means upon the outside of the building adjacent the foundation thereof for engagement with the cross bar for locking the fire escape against swinging movement, said means comprising a fixed member extending laterally from the building, and a vertically swinging normally pendent lever pivoted at its upper end on the outer end of said member, said lever when pendent preventing the disengagement of the cross bar from beneath the laterally extending member.

2. In a fire escape of the class described, a pair of inner and outer spaced chain lengths adapted for disposition on the outside of a building, the inner chain lengths comprising a series of chains, link plates interconnecting the series of chains in the innermost chain lengths, a series of substantially U-shaped step members arranged in vertical spaced relation and having lateral terminals, the crown portion of each U-shaped step being connected with the outer chain lengths, the said lateral terminals of the arms of each U-shaped step being disposed through and journaled and secured in the intermediate portion of each pair of link plates, a window sill engaging unit, the inner chain lengths being secured at their upper ends to said unit, and detachable connections between the outer chain lengths at their upper ends and the window sill attaching unit, whereby the outer chain lengths may be moved inwardly with respect to the inner chain lengths to facilitate the rolling 100 of the ladder when the aforementioned connections are disengaged.

3. In a fire escape of the class described, a pair of inner and outer spaced chain lengths adapted for disposition on the outside of the building, the inner chain lengths comprising a series of connecting links, a series of substantially U-shaped step members arranged in vertical spaced relation and having arms pivotally connected with the inner chain lengths, the crown portion of each U-shaped step member being connected with the outer chain lengths, window sill engaging means connected to the upper ends of the inner chain lengths, and detachable 105 connections between the outer chain lengths at their upper ends, and said window sill engaging means whereby the outer chain lengths may be moved inwardly with respect to the inner chain lengths to facilitate rolling 110 of the ladder or fire escape when the aforementioned connections are disengaged.

In testimony whereof I affix my signature.

WILLIAM KAUTZ.
